HEAT EXCHANGER

Ralph S. Thoresen, Darien, Conn., assignor to
 Petroleum Heat and Power Company, New
 York, N. Y., a corporation of Delaware

Application May 9, 1936, Serial No. 78,745

6 Claims. (Cl. 257—74)

This invention relates to improvements in heat exchangers, and has for one of its objects the provision of a device of the character indicated wherein the fluid to be treated is utilized for driving a rotor which is within the device and provided for the purpose of agitating the fluid being handled and for preventing accumulation of deposits on the wall of the device.

In heat exchangers, especially those employed for heating oil, carbon forms on the inner walls of the heat exchange chamber which is very objectionable due to its heat insulating characteristics.

It is one of the objects of the present invention to provide a heat exchanger with an agitator and rotor which contacts with the inner wall of the chamber of the heat exchanger and serves to keep the same free of carbon or other deposits, this rotor being driven by the fluid to be treated as above mentioned.

Further objects of my invention will be manifest from the following description and the accompanying drawing, in which drawing:

Fig. 1 is a sectional elevation of my improved device;

Fig. 2 is a sectional view on line 2—2 of Fig. 1;

Fig. 3 is a sectional view on the line 3—3 of Fig. 1;

Fig. 4 is a sectional elevation of another form 30 of my improved device;

Fig. 5 is a sectional elevation of still another form; and

Fig. 6 is a cross section of a modified form of heat exchange chamber.

Referring to the drawing in detail, 1 designates a tank, reservoir or other source of supply for the fluid to be treated. A conduit 2 extends from the tank 1 and communicates with a gear pump 3 which may be driven in any suitable manner such as, for example, by an electric motor (not shown). A conduit 4 communicates with the pump 3 and another conduit 5 one leg of which communicates with a heat exchange housing 6. Within the housing 6 a motor 7 is provided adjacent the point where the end of the conduit 5 enters the housing. This motor comprises a pair of gears 8 and 9 meshing with each other and freely mounted on shafts 10 and 11, respectively. The shaft 11 carries a rotor or agitator 12 contained within the inner chamber 13 of the heat exchanger. This rotor as will be seen from Fig. 3 has fins or projections 14 on the surface thereof which frictionally engage the inner wall of the chamber 13 so that as the rotor rotates, it will

keep the walls of the chamber 13 free from carbon or other deposits in addition to agitating the fluid in the chamber.

The motor 7 is driven by the fluid being treated and which, as will be understood, is supplied by the pump 3 under pressure from the conduit 5. This pressure operated motor is not only very efficient but as will be understood its use is an economy in that it eliminates the necessity for a separate drive, including a driving motor, for the 10 rotor.

The chamber 13 is provided with a jacket 15 for the circulation of a heat exchange medium. The nature of this medium of course will depend upon the use of the apparatus. For example, should 15 it be desired to heat the fluid being treated, steam, hot water or the like may be circulated in the jacket 15. On the other hand, should it be desired to cool the fluid, cold water, refrigerating fluid or the like may be circulated through the jacket. 20

The heat exchange medium is supplied to the jacket 15 through conduit 16 and passes out of the same through conduit 17 back to the source of supply or to waste, as desired.

It will be seen from Fig. 1 that the leg 22 of the 25 conduit 5 communicates with the tank or reservoir 1 and serves as a by-pass for the surplus fluid from the pump 3. This leg is provided with a relief valve 18 which opens when the pressure in the line rises to a predetermined value to 30 permit the surplus fluid to return to its source of supply. The fluid after treatment is passed from the heat exchange chamber 15 through conduit 19.

It will be seen that in this embodiment of my 35 invention the rotor 12 is driven by the fluid being treated all surplus fluid being by-passed back to the supply tank.

The form of my invention illustrated in Fig. 4 is similar to that shown in Fig. 1 except that in this form the by-pass conduit 20 is connected to the heat exchange housing back of the motor 7. In this form, therefore, all of the fluid handled by the pump 3 passes the motor 7 to drive the same.

In the form of my invention illustrated in Fig. 5 the return line 30 for surplus fluid communicates with outlet conduit 19 so that all of the fluid handled by the pump 3 necessarily passes the 50 motor 7 to drive the same and through the heat exchanger.

In the forms shown in Figs. 4 and 5 the same reference numerals designate similar parts as shown in Fig. 1.

In Fig. 6 I have illustrated a modification of the rotor 12. In this form the rotor is provided with flexible blades 31 which engage the surface of the inner wall of the chamber 13 of the heat exchanger, instead of the fins 14 shown in Fig. 3.

My improved device is particularly well adapted for use in oil burner systems where it is desired to preheat the oil before the same is fed to the burner. In this use of my device the outlet 30 10 as will be understood communicates with the burner nozzle.

It is to be understood, however, that I do not wish to be limited to this application of my device as obviously the same may be employed in any 15 installation requiring heat exchange.

Neither do I wish to be limited to the precise construction herein illustrated and described inasmuch as various changes and modifications may be made therein without departing from the spirit 20 and scope of my invention.

What I claim is:

1. In a heat exchange apparatus the combination of a reservoir of fluid to be treated, a heat exchange chamber, a housing therefor, a driven pump for transferring the fluid from the said reservoir to said chamber, a conduit leading from the reservoir to said pump, a conduit leading from said pump to said heat exchange chamber, a motor gear in said housing in communication with 25 said conduit, a shaft for said gear extending into said chamber, a rotor mounted on said shaft, the fluid from said conduit driving said motor to rotate said rotor, said rotor having projections on its surface in frictional engagement with the inner walls of the chamber whereby to circulate the fluid in said chamber and to maintain the walls 30 free of deposits.

2. In a heat exchange apparatus the combination of a source of supply of fluid to be treated, 40 a heat exchange chamber, a fluid conduit between said source of supply and said chamber, a driven pump and a fluid driven motor in said conduit, a rotor mounted on the shaft of said motor within said chamber, a plurality of wipers carried on the 45 surface of said rotor adapted to frictionally engage the inner walls of the chamber, and pressure controlled means between said pump and source of supply operable automatically to by-pass the fluid back to the source of supply upon the pressure in the chamber reaching a predetermined 50 value.

3. In a heat exchange apparatus the combina-

tion of a source of supply of fluid to be treated, a heat exchange chamber, a fluid conduit between said source of supply and said chamber, a driven pump and a fluid driven motor in said conduit, a 5 rotor mounted on the shaft of said motor within said chamber, a plurality of wipers carried on the surface of said rotor adapted to frictionally engage the inner walls of the chamber, and pressure controlled means between said pump and source of supply operable automatically to by-pass the 10 fluid back to the source of supply upon the pressure in the chamber reaching a predetermined value, and a jacket about said chamber for the circulation of heat exchange medium to effect 15 heat exchange of the fluid in said chamber. 15

4. In a heat exchange apparatus the combination of a source of supply of fluid to be treated, a heat exchange chamber, a fluid conduit between said source of supply and said chamber, a pump and a fluid driven motor in said conduit, a rotor 20 within said chamber mounted on the shaft of said motor to be driven thereby, and a second conduit leading from the discharge side of said pump back to the source of fluid supply for conducting 25 back to the source of supply fluid delivered by 25 said pump in excess of the demands on the heat exchange chamber.

5. In a heat exchange apparatus the combination of a source of supply of fluid to be treated, a heat exchange chamber, a fluid conduit between 30 said source of supply and said chamber, a pump and a fluid driven motor in said conduit, a rotor within said chamber mounted on the shaft of said motor to be driven thereby, and a conduit leading from the intake end of said chamber back to 35 the source of fluid supply for conducting back to the source of supply fluid passed through said motor in excess of the demands on the heat exchange chamber.

6. In a heat exchange apparatus the combination of a source of supply of fluid to be treated, a heat exchange chamber, a fluid conduit between 40 said source of supply and said chamber, a pump and a fluid driven motor in said conduit, a rotor within said chamber mounted on the shaft of said 45 motor to be driven thereby, a discharge conduit for the said chamber, and a conduit leading from the discharge conduit to the fluid supply for conducting back to the source of supply fluid delivered by said pump in excess of the demands 50 on the heat exchange chamber.

RALPH S. THORESEN.
